UNITED STATES PATENT OFFICE

GEORGE F. HAUF, OF CHICAGO, ILLINOIS

METAL LATTICE WALL

Application filed December 15, 1927. Serial No. 240,112.

My invention relates to metal lattice walls. It relates more particularly to lattice walls, such as are employed to form the walls and gates of poultry or other cages or containers for objects where maximum exposure to atmosphere is desirable.

One object of the invention is to provide an improved metal lattice wall.

Another object is to provide a metal lattice wall which is constructed entirely of materials ordinarily found in sheet metal shops.

A further object is to provide a metal lattice wall which may be entirely constructed by the use of the usual tools and apparatus found in the ordinary sheet metal shop.

A further object is to provide a metal lattice wall which is unusually rigid in construction, which is relatively light in weight and which presents a neat and finished appearance.

A further object is to provide a metal lattice wall which is particularly well adapted for use in poultry cages in connection with the sliding feed and water troughs therefor and which in use precludes the possibility of decapitation of the poultry, when the trough is moved with respect to its adjacent lattice wall.

Other objects and advantages will be more particularly pointed out in the following description in which

Fig. 1 is a perspective view of one form of my improved metal lattice wall during the process of construction, a part thereof being broken away;

Fig. 2 is a perspective view of the finished metal lattice wall, a part thereof being broken away;

Fig. 3 is a sectional view on the line 3—3 of Fig. 2;

Fig. 4 is a fragmentary perspective view of a modified form of metal lattice wall;

Fig. 5 is a fragmentary perspective view of another modified form of a metal lattice wall;

Fig. 6 is a perspective view illustrating the use of the first form of the metal lattice wall (shown in Figs. 1 to 3) in combination with a poultry feed and water trough; and

Fig. 7 is an end elevation of the assembly illustrated in Fig. 6.

In general, the metal lattice wall comprises spaced apart parallel rails A and B of sheet metal having a plurality of transversely disposed iron rods C interconnecting the rails to form a ladder-like wall structure. A reinforcing member D is associated with each of the rails to lend rigidity to the assembly and provide means for its ready attachment.

The metal lattice wall illustrated in Figs. 1 to 3 and in Figs. 6 and 7 will first be described.

Rails A and B are substantially U-shaped in cross-section, the web of rail B being considerably deeper than that of rail A. Each of the rails prior to assembly has laterally enlarged portions or longitudinal beads 10 extending throughout their length adjacent the marginal edges of the rails, and each rail is provided with a plurality of openings 11, through the inner folded edge or apex thereof. One opening in each rail constitutes a complementary pair for receiving opposite ends of the cross bars C, as will be herein-after explained.

Rods or bars C have parallel, laterally bent portions or hooks 12 which, during the process of assembly, are passed through the complementary openings 11. This step of the assembly operation is best accomplished by bringing the inner or folded edges of the rails together with the edge openings which are to constitute the complementary pairs in register with each other. Then, after one hook of each cross rod is threaded through its openings in the two rails, the rails are separated to the length of the cross rods, as shown in Fig. 1.

Heavy iron rods D are placed longitudinally of each of rails A and B within the enlarged portions 10 and the rails are pressed tightly about rods D and the inner bent ends 12 of rods C. This causes rails A and B to assume the contour illustrated in Fig. 2.

The next step in the construction of the lattice wall is that of placing and securing rivets 13 through aligned openings 14 provided at spaced intervals along rail B above enlarged portion 10. It will be noted that

rods D each extend beyond the ends of rails A and B. This is for the purpose of providing support for the wall, either when used as a permanent wall or as a gate. To assure 5 complete engagement of rails A and B and rods D the rails are spot welded at each end, as shown at 15, to rods D.

The lattice wall in use is entirely self-supporting and unusually rigid and resists to a 10 high degree both longitudinally and laterally flexing. Thus no means for support other than the engagement of the ends of the rods D with an adjacent wall or bearing is necessary in the use of the structure, either as a 15 wall or a gate.

In Fig. 4 a modification of the metal lattice wall is illustrated which differs from that form shown in Figs. 1 to 3, inclusive, in that the reinforcing members D' perform the two-fold function of reinforcing rails A' and B' 20 and also of retaining rods C against movement with respect to the rails. Rails A' and B' are U-shaped in cross section, the sides of the U being separated sufficiently to receive 25 metal bars D' therebetween. The inner sides of these bars engage with the laterally bent portions 12 of rods C and the outer sides lie flush with the outer edges of rails A' and B'. Rivets 16 extend through aligned openings in 30 the side walls of the rails and through openings provided in bars D' and when set securely fix the reinforcing bars to the rails. The construction and assembly of this modification is extremely simple and provides a 35 rigid, neat appearing lattice wall.

In Fig. 5 another modification of the metal lattice wall is shown in which rails A'' and B'' are similar in contour to rails A' and B' but have in addition inwardly turned portions 17 which lie parallel to the inner walls 40 of the rails and extend throughout the entire length of the rails to a distance of about one-half the depth thereof.

The distance between the portions 17 and 45 the adjacent inner face of the rails is equivalent to the thickness of the side walls of a U-shaped reinforcing bar D''. Bar D'', as shown in Fig. 5, is received within rails A'' and B'', the sides thereof lying between portions 50 17 of the rails and the adjacent side walls of the rails. In construction these bars are telescoped longitudinally within the rails after rods C are engaged therewith in the manner previously described in connection 55 with the assembly of the preferred form of lattice wall.

The depth of bars D'' is such as to cause the innermost sides thereof to engage with the laterally bent portions 12 of rods C. Thus 60 rods C are securely held against displacement with respect to rails A'' and B''. With the parts thus assembled rivets 18 are passed through aligned openings in rails A'' and B'' and through similar registering openings 65 in bar D''. Rivets 18, when set securely, fix

the bars against disengagement and movement with respect to their associate rails.

One of the important advantages of this modification of the metal lattice wall is that the entire rail structure consists of sheet metal 70 which provides an extremely light, yet rigid, structure which is lower in cost than that modification illustrated in Fig. 4.

In Figs. 6 and 7 I have illustrated in part a poultry cage assembly such as used in poultry 75 cars for which my improved metal lattice wall is especially well adapted.

In this assembly upright angle irons 25 are fixed to the car floors and to the ceiling of the car and serve as supports for frames 26 80 upon which sliding feed or water troughs 27 are mounted. Frames 26 also serve to support sheet metal walls 28 which in part serve to form the poultry cages.

In Figs. 6 and 7 I have illustrated that 85 type of lattice wall which is shown in Figs. 1 to 3, inclusive, as forming the remaining part of that side of the poultry cage contiguous with wall 28. The metal lattice wall is supported upon frames 26 by engagement of those 90 portions of the rod D which extend beyond the end of the rails A and B with frames 26, as shown at 29.

Rail B, being relatively high, extends 95 above the top 30 of trough 27 so that when the trough 27 is drawn from its supporting frame 26 the rearward end 31 of the trough will not contact with rods C to decapitate poultry which have their heads at the time between rods C, as in feeding. This decapitation 100 of poultry is quite a common occurrence with the present construction of lattice walls and feed troughs in poultry cars. It is entirely precluded by the use of the lattice wall herein described.

One of the most important advantages attained by the construction of the lattice wall set forth herein is that all sharp edges and projections usually found in lattice wall construction and caused by the uncovered free and wrapped ends of the rod C about their supporting rails is entirely precluded. This is of particular importance where the lattice wall is used as for a poultry cage since in such constructions which permit the exposure 110 of the ends of the rod C or their convolutions about the rails, the necks and bodies of the poultry are often injured by contact with these parts of the wall. A secondary advantage, of course, is that my present construction is neat in appearance and where a galvanized or rust-proof stock is used for the rod C which is severed in forming the rods, the outer ends of the rods are entirely encased within the rails so that rust at these 115 points is less apt to occur.

Having thus described my invention, what I claim as new and desire to secure by Letters Patent of the United States is:

1. A metal partition wall comprising a pair 120

of laterally spaced apart outwardly facing metal rails substantially U-shaped in cross section, a plurality of parallel metal rods having laterally bent portions at their opposite ends, said portions extending through openings provided in the rails and secured thereto, and reinforcing members disposed between the U-shaped walls of the rails throughout the entire length of the rails and secured thereto.

2. A metal lattice wall comprising a pair of parallel spaced apart rails substantially U-shaped in cross section, a plurality of metal rods having their opposite ends extending through openings provided in the rails and having their extremities bent laterally to engage the adjacent innermost surfaces of the rails and reinforcing members extending longitudinally through the rails between the sides thereof, said rails pressed about said reinforcing members and about the ends of said rods to secure the members and rods against movement with respect to one another and to the rails.

3. A metal lattice wall comprising a plurality of spaced apart outwardly facing rails, each having openings registering with the openings of the opposite rail through the adjacent walls thereof, a plurality of spaced apart metal rods having their opposite ends bent laterally and extended through said openings in said rails and means cooperating with the rails for securing said rods thereto.

4. In a metal lattice wall the combination of a sheet metal rail of substantially U-shaped cross section and provided with a plurality of openings through the apex of the section, a plurality of metal rods, each rod extending through an opening in the rail and having one end bent laterally to form a hook that lies within and parallel to the apex of the rail section, and a reinforcing member lying along and between the sides of the rail section to stiffen the same and projecting beyond the ends of the rail section to serve as a support for the lattice wall.

5. In a metal lattice wall the combination of a sheet metal rail of substantially U-shaped cross section and provided with a plurality of openings through the apex of the section, a plurality of metal rods, each rod extending through an opening in the rail and having one end bent laterally to form a hook that lies within and parallel to the apex of the rail section, and a reinforcing and rod locking member lying along and between the sides of the rail section and wedging the hooked ends of the rods into the apex of the rail section to anchor the rods and rail section together.

6. A metal lattice wall having a sheet metal rail initially of substantially U-shaped cross section and with a plurality of spaced openings arranged along the apex of the section, a plurality of metal rods, each extending

through an opening in the rail and having the end within the rail bent laterally to form a hook lying within and along the rail, and a reinforcing member lying within and along the rail, the rail being tightly wrapped about both the hooks of the rods and the reinforcing member to rigidly anchor together the rail, rods and reinforcing member.

In witness whereof, I hereunto subscribe my name this 2nd day of December, 1927.

GEORGE F. HAUF.
